CLAIM

I claim the ornamental design for outdoor camping lamp, as shown and described.

DESCRIPTION

FIG. 1 is a front view of the outdoor camping lamp.

FIG. 2 is a rear view of the outdoor camping lamp.

FIG. 3 is a left view of the outdoor camping lamp.

FIG. 4 is a right view of the outdoor camping lamp.

FIG. 5 is a top view of the outdoor camping lamp.

FIG. 6 is a bottom view of the outdoor camping lamp; and,

FIG. 7 is a front view of the outdoor camping lamp, with a

hanging hook extending from a top portion of the lamp.

The broken lines illustrated in the figures represent

unclaimed portions of the lamp, and form no part of the

claimed design.
